UNITED STATES PATENT OFFICE

137,535

DESIGN FOR AN IDENTIFICATION TAG DISPLAY UNIT

Peter H. Cohn, Boise, Idaho

Application January 26, 1944, Serial No. 112,336

Term of patent 3½ years

(Cl. D29—23)

To all whom it may concern:

Be it known that I, Peter H. Cohn, a citizen of the United States, residing at 902 Hays Street, Boise, in the county of Ada and State of Idaho, have invented a new, original, and ornamental Design for an Identification Tag Display Unit, of which the following is a specification, reference being had to the accompanying drawing, forming part thereof.

Fig. 1 is a front elevational view of an identification tag display unit showing my new design; and

Fig. 2 is a sectional view taken on line 2—2 of Fig. 1.

I claim:

The ornamental design for an identification tag display unit, as shown.

PETER H. COHN.
